UNITED STATES PATENT OFFICE.

GEORGE MILTON KIRKPATRICK, OF ENNIS, TEXAS.

MACHINE FOR PULLING STALKS.

SPECIFICATION forming part of Letters Patent No. 760,877, dated May 24, 1904.

Application filed July 2, 1903. Serial No. 164,044. (No model.)

To all whom it may concern:

Be it known that I, GEORGE MILTON KIRKPATRICK, a citizen of the United States, and a resident of Ennis, in the county of Ellis and State of Texas, have invented a new and Improved Machine for Pulling Stalks; of which the following is a full, clear, and exact description.

The purpose of the invention is to provide a machine especially designed for pulling up corn and cotton stalks by the roots and breaking the stalks in small pieces when desired and to provide a construction of the character described which will be simple, durable, and economic and wherein the stalks will be guided to the pulling-section of the machine, and the pulling-section may be adjusted to suit the average height of the stalks and bodily raised and lowered at any time to permit the pulling-section to be carried out of the way of obstructions when occasion so demands.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the machine. Fig. 2 is a transverse section through the pulling cylinders or drums, illustrating the application of cutters to one of them. Fig. 3 is a transverse section through the pulling cylinders or drums, the cutters being omitted. Fig. 4 is a longitudinal vertical section taken practically on the line 4-4 of Fig. 1. Fig. 5 is a detail view of a bearing-box for one of the pulling cylinders or drums and a controlling-spring for the box, and Fig. 6 represents plan and end views of the pulling-slats and the cutters employed in the construction of the pulling drums or cylinders.

The axle 10 is provided at each end with a loosely-mounted supporting-wheel 11, and these wheels have suitable boxes at their inner faces concealing pawl-and-ratchet connec-

tions of the usual type between the said wheels and the axles, so that the axle 10 will be turned by the driving-wheels only when the machine 50 is drawn forward.

The axle 10 near each end passes through bearings 13 and 14, and the side pieces 15 of the forward frame-section A are secured to the upper portions of the outer bearings 13, 55 thus bringing the axle 10 below the said forward section A of the frame. The side pieces 15 of this forward frame-section extend rearwardly a desired distance beyond the axle, and the forward members 16 of the said forward frame-section are more or less curved and are connected at their inner ends to opposite sides of the pole or tongue, which extends horizontally rearward to the rear end of the said forward frame-section, and a draft-tree 18 is pivoted on the tongue 17, being usually connected by chains 19 at its ends with the forward members of the forward frame-section A.

The rear frame-section B, completing the 70 main frame of the machine, consists of side pieces 20, which at their forward ends are secured to the upper faces of the inner bearings 14, and adjacent to these bearings 14 the side pieces 20 are curved or inclined downward, 75 as is shown at 21 in Figs. 1 and 4; but for the remaining portion of their length the said side pieces 20 are practically straight, and they extend a predetermined distance beyond the rear of the supporting-wheels 11. The 80 side pieces 20 of the rear frame-section are connected at their rear ends by parallel cross-bars 22 and between their centers and their forward ends by similar parallel bars 23, as is shown in Figs. 1 and 4.

In order to strengthen the rear portion of the forward frame-section A, an arched connecting-bar 24 extends from one side 15 to the other and is provided, preferably, with a central member extending down to the pole 90 or tongue. The driver's seat 25 is supported by a suitable spring-shank 26, and this shank is preferably attached to the tongue 17.

Bearings 27 are located near the left-hand

ends of the parallel cross-bars 22 and 23, the bearings 27 being secured to the said cross-bars, so as to be stationary, and near the opposite ends of the said cross-bars 22 and 23 5 other bearings 28 are slidably mounted on the said cross-bars. These latter bearings, as is shown in Fig. 5, preferably consist of an upper section 28^a and a lower section 29, adapted to enter the spaces between a pair of cross-bars, 10 and at the bottom of the lower section 29 a flange 30 is formed at each side, so as to prevent the bearings from accidentally being drawn from engagement with the cross-bars, yet permitting the bearings to slide freely 15 thereon. Bolts 31 are employed to connect the two sections of the bearings 28, so that by loosening the bolts 31 the lower section of the bearing will drop from the upper one, thus permitting the bearings to be readily detached from their supports.

At the left-hand side of the rear section B of the frame between the cross-bars 22 and 23 a pulling drum or cylinder C is mounted to turn, and adjacent to the right-hand side of 25 the said rear frame-section, also between the cross-bars 22 and 23, a second pulling cylinder or drum C' is mounted to rotate. Each drum or cylinder consists of a series of spoked wheels 32, having central rectangular openings 30 therein, and through the walls of the cylinder or drum C the rectangular portion of a shaft c is passed, which shaft is cylindrical at its ends and is journaled in the fixed bearings 27, while the shaft c' for the drum or cylinder 35 C' is journaled at its ends in the sliding bearings 28, as is shown in Fig. 1. A series of slats 33 is located on the peripheral portions of the wheels of each drum or cylinder, completing the construction thereof, and these 40 slats 33, which may be termed "pulling-slats," are constructed as is shown in Fig. 6, having their ends 34 flattened and provided with apertures 35, whereby the said slats may be secured to the peripheral portions of the end 45 wheels 32 by bolts, screws, or their equivalents. The body portions of the slats or the portions between the ends of a slat are semi-circular, as is shown at 36 in Fig. 6. These slats 33 are so spaced that the slats of one 50 cylinder enter the spaces between the slats of the opposing cylinder, and the slats act as gear-teeth, so that one cylinder imparts movement to the other, and the cylinders turn in opposite directions, both, however, in direction 55 of the space between them. These cylinders or drums are open at each end, and the spaces between the slats enable the dirt and small stones that may be raised to drop into the cylinders or drums and pass out through 60 their bottom portions or at their ends, thus keeping the cylinders or drums free from obstructions.

It is necessary that one of the cylinders or drums should be tension-controlled with re-

spect to the opposing drum or cylinder, so that 65 when the thick butts of stalks pass between them one of the cylinders will give, so as to permit the ready upward passage of the stalk. Therefore the cylinder C' is made movable to and from the cylinder C, and one end of a 70 spring 39 has bearing against the outer end of each of the sliding boxes 28, the other end of each spring having bearing against a block 40, held to slide in the spaces between the pairs of cross-bars 22 and 23. These blocks 75 40 are held in adjusted position by suitable bolts 41, screws, or the like, passed into the blocks through slots 42, made in the cross-bars, as is indicated in Fig. 5. Under this construction it will be observed that greater 80 or less tension may be brought to bear on the movable drum or cylinder C', as may be required.

When it is desirable to cut the stalks in 85 lengths as the stalks are pulled, one of the drums or cylinders—the drum or cylinder C', for example—has sundry of its pulling-slats 33 removed and cutters 37 substituted, as is shown in Fig. 2, one of the cutters being shown in detail in Fig. 6. These cutters are 90 likewise flattened at their ends and are provided at such points with apertures for fastening devices, and the body portion of the cutters is more or less triangular in cross-section, as is shown at 38 in Fig. 6. The pulling-slats 33 may be made of wood, although metal is preferably used for the purpose; but the cutters 37 are made exclusively of metal.

The stationarily-mounted drum or cylinder C is provided at the forward end of its shaft 100 c with a beveled pinion 43, which meshes with a beveled gear 44, loosely mounted on the axle 10, and the inner face of the hub of this beveled gear 44 is provided with a clutch 45, mounted in the usual manner to slide upon 105 the axle 10 or to turn therewith. This clutch 45 is operated through the medium of a foot-lever 46, having a suitable span connection with the clutch, whereby the clutch may be brought into or out of engagement with the 110 aforesaid wheel 44, which may be termed the "driving-wheel."

A hand-lever 47 is pivoted in the tongue 115 17 and extends above and below said tongue. The hand-lever carries a suitable thumb-latch 48, which engages with a rack 49, also carried by the tongue 17, as is shown in Fig. 4. At the lower end of the hand-lever 47 a chain 50 is attached and extends rearward over a pulley on the tongue 17 to a connection with 120 the center of the forward bars 23 of the rear frame-section B.

By means of the hand-lever 47 it will be observed that the rear frame-section B may be raised and lowered, and consequently the 125 pulling cylinders or drums C and C' may be raised and lowered from or to the ground, as occasion may require—as, for example, in

avoiding an obstruction and bringing the drums quickly down to operative position again after the obstruction is passed.

The rear end of the rear frame-section B is 5 adjusted separately, so that in operation the drums or cylinders C and C' may be brought nearer to or farther from the ground in the following manner: Bearings 51 are attached to the rear member of the rear cross-bars 22, 10 and in these bearings the shanks 52 of caster-wheels 53 are loosely mounted, and above and below the said bearings on the said shanks 52 of the caster-wheels sleeves 54 and 55 are located, being adjustably secured to the shanks 15 52 by set-screws or their equivalents.

In order that the stalks may be accurately directed to the contacting-points between the two drums or cylinders C and C', I employ what I term "gathering-arms" 56, which are 20 attached usually to the rear end of the forward frame-section A at each side of the tongue or pole 17 and are carried forward beyond the front end of the said frame, where the arms 25 56 are curved outwardly in opposite directions, forming directing members 56^a, as is particularly shown in Fig. 1.

The machine is operated by the driver from his seat and is of simple and durable construction, as one man and one team can operate the 30 machine under all circumstances. The cylinders or drums C and C' commence to pull the stalks at their tops, thus uprooting them, and should the stalks break off during the gripping and pulling operation the cylinders will 35 continue to take hold of the stalks unless they should break off near to the ground. As has been stated, by reason of one drum or cylinder being tension-controlled and having sliding movement relative to the other ample 40 space is provided between the two drums or cylinders for the ready passage of the thick sections of the stalks, and the cylinders or drums will continue to take hold of the stalks unless they should break off near to the ground. 45 The gathering-arms 56 gather and convey the stalks to the point of contact between the pulling drums or cylinders, which immediately draw them from the ground.

The machine does not require a skilled person to operate it and can be driven over stumps or other obstructions by operating the hand-lever 47. All parts are interchangeable, and therefore can be easily repaired and parts substituted. The pulling device may be readily 50 raised and lowered as occasion may demand and operated at any desired height from the ground.

It will be understood that changes in the 55 form and proportions of the minor details of construction may be resorted to without departing from the spirit of the invention.

Having thus described my invention, I claim as new and desire to secure by Letters Patent—

1. In a machine for pulling stalks, opposing

cylinders having slatted body portions in 65 mesh, one cylinder having sliding relation to the other, cutters alternating with the slats of one of the cylinders, serving likewise the purpose of a slat, supports for the cylinders, and means for raising and lowering the cylinders upon their supports.

2. In a machine for pulling stalks, oppositely-located pulling-cylinders mounted to revolve and having their body portions in mesh, one cylinder having tension-controlled 75 sliding relation to the other, which other cylinder is mounted in stationary bearings, cutters carried by one of the cylinders, alternating with the slats thereon and adapted to enter the spaces between the slats of the opposing cylinder, the said cutters extending practically the length of the cylinder, and a driving mechanism for the stationarily-mounted cylinder, as described.

3. In a machine for pulling stalks, a forward 85 wheel-supported frame, a rear frame mounted to turn in vertical relation with the wheel-supported frame, pulling-cylinders mounted to revolve in the rear frame, having open-slatted body portions in mesh, means for giving one cylinder tension-controlled sliding 90 relation to the other, which other cylinder is mounted in stationary bearings, both cylinders having a downward and rearward inclination, cutters carried by one of the cylinders, 95 alternating with the slats thereof and adapted to enter the spaces between the slats of the opposing cylinder, a driving connection between the wheel-supported forward frame and the stationarily-mounted cylinder, means carried by the forward wheel-supported frame 100 for raising and lowering the rear frame carrying the cylinders, and caster-wheels, adjustably mounted at the rear end of the rear frame of the machine, for the purpose described. 105

4. In a machine for pulling stalks, a forward wheel-supported frame, a rear frame extending therefrom, a driving mechanism carried by the wheel-supported frame, pulling-cylinders mounted to revolve in the rear frame, 110 each cylinder being provided with pulling peripheral slats and one of the cylinders with interposed cutters parallel with the slats, extending practically the length of the said cylinder, the bodies of the said cylinders being 115 in mesh throughout the length of the slats and cutters, and a driving connection between one of the cylinders and the driving mechanism carried by the forward wheel-supported frame, supports for the cylinders, and devices 120 for simultaneously raising and lowering the cylinders upon their supports.

5. In a machine for pulling stalks, a supporting-frame, cylinders mounted to turn in the bearings of the said frame, one cylinder 125 having sliding relation to the other, each cylinder comprising a series of body-wheels secured to their carrying-axle, and slats ar-

ranged at intervals at the peripheral portions of the said wheels, the slats of one cylinder being in mesh with the slats of the opposing cylinder, cutters alternating with the slats of one cylinder and arranged for meshing engagement with the opposing cylinder, and raising and lowering devices for the cylinders, as set forth.

In testimony whereof I have signed my name to this specification in the presence of two subscribing witnesses. 10
